UNITED STATES PATENT OFFICE.

FREDERICK W. TAMKE, OF NEW YORK, N. Y.

DISPENSING CAN.

Application filed September 22, 1925. Serial No. 57,853.

This invention is an improvement in dispensing cans and more particularly in cans of sheet material, having pouring spouts or nozzles.

5 Cans, particularly of the type used for containing liquids such as edible oils, are usually provided with a filling opening having a cup shaped insert forming a stopper for closing the opening, which may be removed, or perforated, to permit discharge 10 of the contents.

For convenience in packing, the cans are usually of similar size and regularly shaped, as for instance substantially rectangular in 15 cross section, and the cans usually have inset ends. With cans of this character, when any portion of the contents is discharged a part thereof will be dammed back by the upstanding flange encircling the top, and 20 such part, or at least a portion thereof will remain outside the can.

This remaining part catches foreign bodies, such as dust, insects and the like, and easily becomes rancid through exposure to 25 the atmosphere, with the possibility of contamination of the remainder of the can's contents.

Furthermore with the type of discharge 30 above described, there is nothing to direct the stream of outflowing oil to the place desired, and there is a consequent liability to wastage.

Since for convenience of packing, it is desirable that the cans fit close against one 35 another, and that the tiers of the cans rest flat one upon the other, any form of pouring nozzle which extends beyond the normal overall dimensions of the can is undesirable since such nozzles would interfere with the 40 close packing of the cans.

It is also desirable in cans of this character, that the can be fluid tight, that is, that the contents be enclosed by an unbroken or imperforate wall, until they reach the hands 45 of the consumer. When the cans are filled and tightly sealed, they should remain in this condition until opened for use. That is, discharge openings necessary for the removal of the contents should be made by the 50 consumer.

One of the primary objects of the present invention is the provision of a form of discharge including a directing nozzle, normally within the plane of the can end, but 55 capable of movement into directing position extending beyond the can wall.

Another object is the provision of a can, wherein after the can is filled and sealed, the contents are enclosed and insured against contamination by an unbroken or imperforate 60 wall, which first is broken by the consumer.

Another object is the provision of a separable or frangible portion at the nozzle, capable of easy separation to provide a 65 discharge opening.

Another object is the provision of a nozzle arranged to cooperate with the opening left by the removal of the frangible portion in the manner of a valve, to close the opening 70 when the nozzle is out of pouring position, and to open the opening when in pouring position.

With these and other objects in view, the invention consists in the construction and 75 novel combination of parts fully described hereinafter, illustrated in the accompanying drawings, and pointed out in the claims appended hereto, it being understood that various changes in the form, proportion, size 80 and minor details of construction within the scope of the claims, may be resorted to without departing from the spirit of the invention.

In the drawings forming a part hereof, 85 Fig. 1 is a perspective view of a can constructed in accordance with the invention, with the nozzle in inoperative or packing position.

Fig. 2 is perspective of the top of the can 90 with the nozzle in pouring position.

Fig. 3 is a side view with a part in section, showing the nozzle in operative position.

Fig. 4 is an enlarged perspective of a 95 corner of the can.

The present embodiment of the invention is shown in connection with a can of usual construction, substantially rectangular in cross section in all dimensions, and composed of a tubular body 1, and plane ends 2, which are inset as shown. The insetting of the ends provides a marginal rib 3 at each end of the can, this rib being formed by the interlock and seam between the end and the 100 body.

In one corner of one end, the can is provided with a depression formed by offsetting laterally a portion of the end, the offset portion, however, remaining an integral 110 part of the end of the depression, a portion 4 of circular form and an annular portion

5 encircling the portion 4 and of less depth. Referring to Fig. 3 it will be seen that the bottom of the part 4 of the depression inclines slightly downward away from the 5 corner, and towards the center of the can. This is true also of the portion 5 which is of greatest depth at the side remote from the corner, and gradually decreases in depth toward the corner to be substantially flush 10 with the end at the corner.

In the part 4 of the depression which is nearest the corner, a circular portion 6 is indicated to form a discharge opening. This portion may be merely indicated, or it may 15 be partially separated from the body of the end to be easily punched out, thereby to provide a discharge opening. Preferably the portion is partially separated, so that it easily may be punched out of the plane of the 20 bottom of the depression.

A discharge spout or nozzle is rotatably connected with the can end, at the depression 4. This spout comprises a substantially cup or nipple shaped portion 7, and an integral scoop or spoon shaped radial extension 8. Referring to Fig. 3, it will be seen that the portion 7 of the nozzle is inserted 25 in the portion 4 of the depression, and is rotatably held therein by expanding the nipple to fill the depression. The side wall 9 of the part 4 of the depression, is slightly undercut as shown, so that when the nipple is expanded, a firm connection is established, but a connection which permits the spout or 30 nozzle to rotate with respect to the can, from the position of Fig. 1 to that of Fig. 2.

The extension 8 is of a length such that when turned to position of Figs. 2 and 3, the free ends thereof will extend above the rib 3, and beyond the side wall of the can, thereby 40 to permit the stream of oil beyond the can. Because of the inclination of the bottom of the depression 4-5, all of the spout or nozzle moves within the plane of the free edge 45 of the rib 3, when the nozzle is turned into the inoperative position of Fig. 1. The extension 8 will lie close to the can end, and will not interfere with the stacking of another can thereon, even were said can laid 50 on its side. The portion 7 of the cup or nip-

ple shape part of the spout has an opening 10 eccentric to the nipple, and so arranged, that when the extension is in the position of Fig. 2 it will register with the indicated or partially separated portion 6 of the depression bottom. When it is desired to discharge the can contents, the nozzle is turned to the position of Fig. 2, and the portion 6 is punched out. When now the can is tilted, the contents flow out through the registering 55 opening, and over the extension. When a sufficient quantity has been poured, the spout is turned into the position of Fig. 1, thus closing the opening at 6.

With the improved spout or nozzle, the top of the can may be retained in a clean aseptic condition, and there is no waste of the contents of the can, either by mis-direction, or by retention on the can top. Furthermore when the spout is in the position 70 of Fig. 1, loss by overturning of the can is prevented.

I claim:

A can having an inset end providing at the said end an upstanding marginal rib, the end having an integral portion thereof near the rib offset inwardly to provide a depression, and a pouring nozzle including a cup shaped body and a directing spout extending substantially radially therefrom, the body journaled within the depression to rotate on an axis inclining at its top away from the rib, thereby to move the directing spout within the rib and below the top thereof when the nozzle is turned with the directing spout inwardly, and to extend the spout beyond the rib and above the top thereof when the nozzle is turned to bring the directing spout outwardly, the body and depression having cooperating means to rotatably hold the body in the depression, the body of the nozzle having an opening to register with an opening formed in the bottom of the depression when the contents of the can are to be dispensed.

Signed at New York city in the county of New York and State of New York, this 18th day of Sept., A. D. 1925.

FREDERICK W. TAMKE.
